COMBINED THREAD PICKER AND SEAM RIPPER

Rita L. Kyes, St. Louis, Mo. (The Village Inn, Elsah, Ill.)

Filed Jan. 18, 1960, Ser. No. 59,094

Term of patent 14 years

(Cl. D3—19)

FIG. 1

FIG. 2

FIG. 3

FIG. 4

FIG. 5

FIG. 6

FIG. 7

FIG. 1 is a side perspective view of a combined thread picker and seam ripper showing my new design;

FIG. 2 is a side elevational view thereof;

FIG. 3 is an elevational view of the side opposite to that disclosed in FIG. 2;

FIG. 4 is a top plan view thereof as seen from FIG. 2;

FIG. 5 is a bottom plan view thereof;

FIG. 6 is an end elevational view thereof as seen from the right of FIG. 2; and

FIG. 7 is an end elevational view thereof as seen from the left of FIG. 2.

I claim:

The ornamental design for a combined thread picker and seam ripper, substantially as shown.
